UNITED STATES PATENT OFFICE.

CLINTON PAUL TOWNSEND, OF WASHINGTON, DISTRICT OF COLUMBIA.

ELECTROLYTIC PROCESS.

SPECIFICATION forming part of Letters Patent No. 779,384, dated January 3, 1905.

Original application filed April 12, 1902, Serial No. 102,582. Divided and this application filed May 11, 1904. Serial No. 207,490.

To all whom it may concern:

Be it known that I, CLINTON PAUL TOWNSEND, a citizen of the United States, residing at Washington, in the District of Columbia, 5 have invented certain new and useful Improvements in Electrolytic Processes, of which the following is a specification.

This process is intended for the electrolysis of solutions, especially aqueous solutions of 10 alkali-metal salts, and is directed to the recovery of a cathode product of electrolysis.

According to the process a product or products of the electrolysis, whether primary or secondary, is liberated in the presence of a 15 liquid which is substantially immiscible with and inert toward said product or products and which serves several important functions, hereinafter specified.

As a specific example of my process I will 20 describe the electrolysis of an aqueous solution of sodium chlorid to produce caustic soda and chlorin, referring to the accompanying drawings, wherein the figure is a transverse vertical section of one type of cell.

The cell shown comprises a central compartment 1, containing an anode or anodes 2 and one or more lateral or cathode compartments 3, shown as two in number, the lateral compartments being separated from the central 25 compartment by cathodes 4 and diaphragms 5. The anodes 2, shown as two in number, may be plates of Acheson graphite, carried by a conductor-bar 2', also of graphite, or they may be of any other suitable construction and material. The diaphragms 5 are of asbestos or other suitable pervious material, supported between the perforated sheet-metal or wire-gauze cathodes 4 and the plates 6, which have numerous small perforations, except at their upper portions. The plates 6, which may be of hard rubber, earthenware, hardened asbestos, or other suitable non-conducting material, serve to support the diaphragm and may be omitted if the diaphragm 35 is of self-supporting material. The cathodes are shown as inclined slightly from the vertical; but such inclination is not essential.

7 7 represent plates, preferably of iron, adjacent and approximately parallel to the cathodes. These plates terminate a slight dis-

tance above the bottom of the cathode-compartments and below the top for a purpose hereinafter described. The position of the plates 7 is such as to provide a relatively narrow space between said plates and the cathodes and a relatively wide space between said plates and the outer wall of the cathode-compartments.

8 8 are coils suitably connected and employed for heating or cooling the liquid in the 60 cell to maintain the temperature of the electrolyte at any desired point. Considerable economy of current can be effected by maintaining the electrolyte at a suitable temperature above normal.

As illustrated, the cathode-compartments 3 3 are somewhat deeper than the central or anode compartment 1 and are provided with valve-regulated drain-pipes 9 9, communicating with the main conduit 10.

In operation the central compartment is filled with sodium-chlorid solution, and a continuous flow is preferably maintained through this compartment from below upward, the inlet 11 and outlet 12 being provided for this 75 purpose. The lateral compartments are filled to or above the top of the plates 7 with a liquid which is substantially immiscible with and inert toward the cathode product, which product in the present instance is sodium hydrate. It is important that the liquid used in the lateral compartments should be of such character as to separate readily from the caustic and that it should be so inert with respect to the caustic that it will not undergo 80 any rapid injurious change or modification in use. Of such liquid the non-saponifying oils may be taken as an example. Upon the passage of the current chlorin is liberated at the anode and sodium at the cathode. The chlorin 85 escapes from the cell and may be collected and used as desired. The sodium is set free at the cathode in the presence of the inert immiscible liquid and is in part or entirely oxidized by the solution in the diaphragm or percolating through the diaphragm. The caustic solution so formed under the oil detaches itself freely from the cathode and is withdrawn 90 from the cell through the pipes 9. The hydrogen which results from the reaction es- 95 100

apses upward through the narrow space between the cathodes and the plates 7, thereby inducing a strong circulation of the oil, which further aids in detaching the globules of caustic solution, thereby removing them quickly from the field of the electrolytic action.

The use of an inert liquid immiscible with the cathode product for the purpose of collecting such product effects many important advantages, as follows:

First. The product is formed and collected under a seal of said immiscible liquid and is thereby protected from all effects due to the contact of atmospheric gases. In the case of 15 caustic soda, for instance, the sealing liquid prevents the production of sodium carbonate. It also prevents the production of carbonates of such metals as calcium and magnesium, which may be present in an unpurified brine and 20 which would act to obstruct the diaphragm and gradually to reduce its porosity. It also prevents evaporation of the liquid which carries the product in solution and consequent deposition therefrom in the diaphragm or on 25 the cathode of the less soluble constituents.

Second. It effects the positive removal of the product from the electrode, an effect probably due in part at least to the difference in the adhesive power of the two liquids--as, 30 for instance, the caustic solution and the mineral oil—for the material of the electrode. For instance, oil adheres closely to such surfaces, and it follows that the caustic solution, being unable to displace the oil, assumes at 35 once the form of a globule and freely detaches itself from the surface. Since the amount of diffusion of one liquid into another is dependent upon the time during which they remain in contact, this rapid removal of the caustic 40 through the agency of the oil is most effective in preventing diffusion of the caustic into the liquid in the anode-compartment.

Third. This removal of the caustic from the cathode is further aided by the fact that the 45 hydrogen, which is a product of the reaction between the sodium and the water of the brine and which is set free concurrently with the production of the caustic, is liberated under the hydrostatic pressure of the oil instead 50 of merely expanding into an atmosphere. The hydrogen is compressed into bubbles which acquire a positive energy and direction of movement and greatly assist in detaching globules of caustic.

Fourth. The hydrogen, moving rapidly upward between the cathode and the plate 7, as before mentioned, imparts a rapid movement of circulation to the oil, which causes the oil to effectively and positively strip from the 60 cathode the particles or globules of caustic solution. This rapid and useful movement of circulation is effected automatically and without extraneous assistance by the escaping hydrogen. The immiscible liquid therefore 65 operating through its own adhesion to the

cathode-surface, through the direction which it gives to the bubbles of hydrogen, and through its rapid movement of circulation, effects a practically instantaneous removal of the caustic from the surface of the cathode and 70 from the field of electrolysis.

Fifth. The removal of the caustic from the cathode being effected in part by the hydrogen-bubbles escaping under the oil and in part by the stripping action of the circulating 75 oil thereby induced, as above described, it follows that an increase of current density, by which both of these favorable effects are increased, will operate advantageously within certain limits. In practice I find that I am 80 enabled to utilize current densities equal to or exceeding one ampere per square inch of cathode area with a high degree of efficiency, thus giving to the apparatus a very large capacity.

Sixth. During the relatively slow downward movement of the oil in the large compartment between the plate 7 and the cell-wall the caustic carried by the oil is permitted to separate therefrom and is deposited in the 90 lower portion of the cell and in the drainage system, whence it is withdrawn as desired. The caustic is thus automatically deposited as formed out of the circulating path of the oil and out of the field of electrolytic action and 95 is positively insulated from the electrolytic field.

Seventh. The oil further acts in a marked degree to protect the diaphragm from the products of the electrolysis. I find that a 100 fibrous material of vegetable or animal origin may be employed and that the film of oil which covers or coats the fiber serves to a large extent to prevent contact therewith of the products of electrolysis, and hence to prevent their 105 corrosive action.

Eighth. The oil affords a convenient means for regulating the rate of flow of the electrolyte through the diaphragm, and hence the concentration of caustic solutions produced at 110 any particular current density. By raising or lowering the oil-level the amount of percolating liquid may be decreased or increased at will, and this effect may be supplemented by a variation in the level of the liquid in the 115 anode-compartment. If the rate of flow through the diaphragm be greatly diminished, the caustic is seen to be detached from the cathode in the form of flakes or flocculent masses or particles.

Ninth. The oil serves to positively support the diaphragm, and particularly those portions of the same which lie between the meshes of the cathode, and which therefore do not derive support therefrom. The tendency of the 125 diaphragm to yield to the pressure of the liquid in the anode-compartment and to become perforated is thereby obviated.

Tenth. The hydrostatic pressure of the anode liquor varies from top to bottom of the 130

diaphragm, and hence the percolation through portions of the diaphragm at different levels would vary through wide limits in the absence of a balancing hydrostatic pressure. 5 The effect of the balancing or partially balancing hydrostatic pressure of the oil is to compensate in part for such differences and to equalize the flow through different portions of the diaphragm.

10 Eleventh. The heating or cooling means for varying the temperature of the oil, and hence of the electrolyte, afford a convenient means for control in this respect.

It is to be understood that the foregoing 15 statement of advantages is merely illustrative and is not to be construed as in any way limiting the scope of my process as defined in the claims.

20 In operating the cell I have noted a very marked storage effect, the yield at first being low, but rising rapidly to figures closely approximating those required by theory. On ceasing to pass current through the cell a strong secondary current appears, apparently 25 due to the oxidation of sodium which had been deposited upon the cathode and protected from oxidation. This secondary current persists for a long period, and caustic-soda solution is delivered from the cell during the whole of 30 such period. In case it is desired to interrupt the passage of current through the cell the electrical connections may be so changed as to cause this secondary current from two or more cells to pass through other cells, whereby such 35 current is employed to produce a useful effect. Such procedure should not be permitted to continue too long, however, as some oxidation or solution of the cathode may occur.

40 The apparatus herein described is claimed 40 in my copending application, Serial No. 207,227, filed May 10, 1904.

This application is a division of my application, Serial No. 102,582, filed April 12, 1902.

45 I claim—
1. The process of electrolyzing solutions, which consists in passing an electric current through the solution to a cathode, and recovering a cathode product of electrolysis by means of a liquid which is substantially immiscible with and inert toward said product, as set forth.

50 2. The process of electrolyzing solutions of alkali-metal salts, which consists in passing an electric current through the solution to a cathode, converting the alkali metal deposited on said cathode into a compound, and recovering said compound by means of a liquid which is substantially immiscible with and inert toward the compound, as set forth.

55 3. The process of electrolyzing solutions, which consists in passing an electric current through the solution and a diaphragm to a cathode, and recovering a cathode product of electrolysis by means of a liquid which is sub-

stantially immiscible with and inert toward said product, as set forth.

4. The process of electrolyzing solutions of alkali-metal salts, which consists in passing an electric current through the solution and a diaphragm to a cathode, converting the alkali metal deposited on said cathode into a compound, and recovering said compound by means of a liquid which is substantially immiscible with and inert toward the compound, as set forth. 75

5. The process of electrolyzing solutions, which consists in passing an electric current through the solution and a diaphragm to a cathode, and recovering a cathode product of electrolysis by means of a non-saponifying oil, as set forth. 80

6. The process of electrolyzing solutions of alkali-metal salts, which consists in passing an electric current through the solution and a diaphragm to a cathode, converting the alkali metal deposited on said cathode into a compound, and recovering said compound by means of a non-saponifying oil, as set forth. 85

7. The process of electrolyzing solutions, which consists in interposing a diaphragm and a previous cathode between a body of the solution and a body of a liquid which is substantially immiscible with and inert toward a cathode product of the electrolysis, and passing an electric current through said solution and diaphragm to said cathode, whereby said product is removed from the field of electrolysis, as set forth. 90

8. The process of electrolyzing solutions of alkali-metal salts, which consists in interposing a diaphragm and a previous cathode between a body of the solution and a body of a liquid which is substantially immiscible with and inert toward the alkali-metal compound produced, passing an electric current through said solution and diaphragm to said cathode, converting the alkali metal deposited on said cathode into a compound, and recovering said compound by means of said liquid, as set forth. 100

9. The process of electrolyzing solutions, which consists in interposing a diaphragm and a previous cathode between a body of the solution and a body of a non-saponifying oil, and passing an electric current through said solution and diaphragm to said cathode, whereby a product is removed from the field of electrolysis, as set forth. 115

10. The process of electrolyzing solutions of alkali-metal salts, which consists in interposing a diaphragm and a previous cathode between a body of the solution and a body of a non-saponifying oil, passing an electric current through said solution and diaphragm to said cathode, converting the alkali metal deposited on said cathode into a compound, and recovering said compound by means of said oil, as set forth. 120

11. The process of electrolyzing solutions, which consists in passing an electric current through the solution to a cathode, recovering a cathode product of electrolysis by means of a liquid which is substantially immiscible with and inert toward said product, and circulating said liquid in contact with said cathode, as set forth. 5
12. The process of electrolyzing solutions, 10 which consists in passing an electric current through the solution to a cathode, recovering a cathode product of electrolysis by means of a liquid which is substantially immiscible with and inert toward said product, and circulating said liquid in contact with said cathode by means of a gaseous product of the electrolysis, as set forth. 15
13. The process of electrolyzing solutions of alkali-metal salts, which consists in passing an electric current through the solution to a cathode, converting the alkali metal deposited on said cathode into a compound, recovering said compound by means of a liquid which is substantially immiscible with and inert toward the compound, and circulating said liquid in contact with said cathode by means of a gaseous product of the electrolysis, as set forth. 20
14. The process of electrolyzing solutions, 25 which consists in passing an electric current through the solution and a diaphragm to a cathode, recovering a cathode product of electrolysis by means of a liquid which is substantially immiscible with and inert toward said product, and circulating said liquid in contact with said cathode, as set forth. 30
15. The process of electrolyzing solutions, 35 which consists in passing an electric current through the solution and a diaphragm to a cathode, recovering a cathode product of electrolysis by means of a liquid which is substantially immiscible with and inert toward said product, and circulating said liquid in contact with said cathode by means of a gaseous product of the electrolysis, as set forth. 40
16. The process of electrolyzing solutions of alkali-metal salts, which consists in passing an electric current through the solution and a diaphragm to a cathode, converting the alkali metal deposited on said cathode into a compound, recovering said compound by means of a liquid which is substantially immiscible with and inert toward the compound, and circulating said liquid in contact with said cathode by means of a gaseous product of the electrolysis, as set forth. 45
17. The process of electrolyzing solutions, 50 which consists in passing an electric current through the solution and a diaphragm to a cathode, recovering a cathode product of electrolysis by means of a liquid which is substantially immiscible with and inert toward said product, and circulating said liquid rapidly upward along said cathode and slowly downward at a distance from said cathode, as set forth. 55
18. The process of electrolyzing solutions, 60 which consists in passing an electric current through the solution and a diaphragm to a cathode, recovering a cathode product of electrolysis by means of a liquid which is substantially immiscible with and inert toward said product, and circulating said liquid rapidly upward along said cathode and slowly downward at a distance from said cathode by means of a gaseous product of the electrolysis, 70 as set forth. 75
19. The process of electrolyzing solutions of alkali-metal salts, which consists in passing an electric current through the solution and a diaphragm to a cathode, converting the alkali metal deposited on said cathode into a compound, recovering said compound by means of a liquid which is substantially immiscible with and inert toward the compound, and circulating said liquid rapidly upward along said cathode and slowly downward at a distance from said cathode by means of a gaseous product of the electrolysis, 80 as set forth. 85
20. The process of electrolyzing solutions, 85 which consists in interposing a diaphragm and a pervious cathode between a body of the solution and the body of a liquid which is substantially immiscible with and inert toward a cathode product of the electrolysis, passing an electric current through said solution and 90 diaphragm to said cathode, whereby said product is removed from the field of electrolysis, and controlling the temperature of the electrolyte by suitably varying the temperature of said liquid, as set forth. 95
21. The process of electrolyzing solutions of alkali-metal salts, which consists in interposing a diaphragm and a pervious cathode between a body of the solution and a body of a liquid which is substantially immiscible with and inert toward the alkali-metal compound produced, passing an electric current through said solution and diaphragm to said cathode, converting the alkali metal deposited on said cathode into a compound, recovering said compound by means of said liquid, and controlling the temperature of the electrolyte by suitably varying the temperature of said liquid, as set forth. 105
22. The process of electrolyzing solutions, 110 which consists in liberating a product of the electrolysis in the presence of a liquid which is substantially immiscible with and inert toward said product, as set forth. 115
23. The process of electrolyzing solutions of alkali-metal salts, which consists in liberating and oxidizing the alkali metal in the presence of a non-saponifying oil, as set forth. 120
24. The process of electrolyzing aqueous solutions of alkali-metal salts, which consists in liberating the alkali metal in the presence of a liquid which is substantially immiscible with and inert toward alkali-metal hydroxids, and oxidizing said metal by the water in the solution, as set forth. 125

25. The process of electrolyzing aqueous solutions of alkali-metal salts, which consists in liberating the alkali metal in the presence of a non-saponifying oil, and oxidizing said metal by the water in the solution, as set forth.

26. The process of electrolyzing aqueous solutions of alkali-metal salts, which consists in interposing a diaphragm and a pervious cathode between a body of the solution and a body of a liquid which is substantially immiscible with and inert toward alkali-metal hydroxids, passing an electric current through said solution and diaphragm to said cathode, oxidizing the alkali metal deposited on said cathode by the water in said solution, and withdrawing the alkali-metal hydroxid through said body of liquid, as set forth.

27. The process of electrolyzing aqueous solutions of alkali-metal salts, which consists in interposing a diaphragm and a pervious cathode between a body of the solution and a body of a non-saponifying oil, passing an electric current through said solution and diaphragm to said cathode, oxidizing the alkali metal deposited on said cathode by the water in said solution, and removing the alkali-metal hydroxid through said body of oil, as set forth.

In testimony whereof I affix my signature in presence of two witnesses.

CLINTON PAUL TOWNSEND.
